[57] CLAIM

The ornamental design for an illuminator housing, as shown
and described.

DESCRIPTION

FIG. 1 is a perspective view showing our new design, in a
vertical orientation;
FIG. 2 is a front elevational view thereof;
FIG. 3 is a side elevational view thereof;
FIG. 4 is a top plan view thereof;
FIG. 5 is a side elevational view thereof, showing the side
opposite that seen in FIG. 3;
FIG. 6 is a rear elevational view thereof; and,
FIG. 7 is a bottom plan view thereof.
